(57) **CLAIM**

The ornamental design for an interdental cleaner, as shown and described.

DESCRIPTION

FIG. 1.1 is a perspective view of my design; FIG. 1.2 is a front view of the design of FIG. 1.1; FIG. 1.3 is a rear view of the design of FIG. 1.1; FIG. 1.4 is a top view of the design of FIG. 1.1; FIG. 1.5 is a bottom view of the design of FIG. 1.1; FIG. 1.6 is a left view of the design of FIG. 1.1; FIG. 1.7 is a right view of the design of FIG. 1.1; FIG. 2.1 is a perspective view of another design; FIG. 2.2 is a front view of the design of FIG. 2.1; FIG. 2.3 is a rear view of the design of FIG. 2.1; FIG. 2.4 is a top view of the design of FIG. 2.1; FIG. 2.5 is a bottom view of the design of FIG. 2.1; FIG. 2.6 is a left view of the design of FIG. 2.1; FIG. 2.7 is a right view of the design of FIG. 2.1; FIG. 3.1 is a perspective view of another design; FIG. 3.2 is a front view of the design of FIG. 3.1; FIG. 3.3 is a rear view of the design of FIG. 3.1; FIG. 3.4 is a top view of the design of FIG. 3.1; FIG. 3.5 is a bottom view of the design of FIG. 3.1; FIG. 3.6 is a left view of the design of FIG. 3.1; FIG. 3.7 is a right view of the design of FIG. 3.1; FIG. 4.1 is a perspective view of my design; FIG. 4.2 is a front view of the design of FIG. 4.1; FIG. 4.3 is a rear view of the design of FIG. 4.1; FIG. 4.4 is a top view of the design of FIG. 4.1; FIG. 4.5 is a bottom view of the design of FIG. 4.1; FIG. 4.6 is a left view of the design of FIG. 4.1; FIG. 4.7 is a right view of the design of FIG. 4.1; FIG. 8.1 is a perspective view of another design; FIG. 8.2 is a front view of the design of FIG. 8.1; FIG. 8.3 is a rear view of the design of FIG. 8.1; FIG. 8.4 is a top view of the design of FIG. 8.1; FIG. 8.5 is a bottom view of the design of FIG. 8.1; FIG. 8.6 is a left view of the design of FIG. 8.1; FIG. 8.7 is a right view of the design of FIG. 8.1; FIG. 12.1 is a perspective view of another design; FIG. 12.2 is a front view of the design of FIG. 12.1; FIG. 12.3 is a rear view of the design of FIG. 12.1; FIG. 12.4 is a top view of the design of FIG. 12.1; FIG. 12.5 is a bottom view of the design of FIG. 12.1; FIG. 12.6 is a left view of the design of FIG. 12.1; and, FIG. 12.7 is a right view of the design of FIG. 12.1.
